HANDBAG

Percy Barker, San Mateo County, Calif., assignor
to Plastic Specialty Company, San Francisco,
Calif., a corporation of California

Application March 26, 1949, Serial No. 83,673

1 Claim. (Cl. 229—46)

1

My invention relates to containers for personal use and particularly to boxes or bags which can be readily carried by the user as a container for miscellaneous items for example, knitting, lunches, personal effects and the like.

It is an object of my invention to provide a hand bag which is effectively identified as a personal article although its general appearance may be identical with many other hand bags.

A further object of the invention is to provide a hand bag of a construction so that the name of the user will be prominently displayed despite variations in position and in environment of the hand bag.

Another object of the invention is to provide a hand bag in which the parts are relatively rigid, yet in which the identification of the user can be readily introduced or as readily removed or changed.

Another object of my invention is to provide a simple, attractive, inexpensive and personalized hand bag.

Another object of my invention is to provide a way of identifying a hand bag without requiring skilled work of engraving or the like at the point of sale of the hand bag.

Other objects, together with the foregoing, are attained in the embodiment of my hand bag described in the accompanying description and illustrated in the accompanying drawings in which

Figure 1 is a perspective view of a hand bag constructed in accordance with my invention.

Figure 2 is a fragmentary view to an enlarged scale in cross-section the plane of which is indicated by the line 2—2 of Figure 1.

Figure 3 is a perspective of a name sheet utilized in connection with my hand bag and as illustrated in Figures 1 and 2.

While in its commercial forms, the hand bag of my invention can be embodied in a number of variant ways, it has with considerable success been embodied as shown herein. In this instance I provide a container body 6 which is of any suitable shape, yet preferably is a circular-cylindrical drum of an appropriate light, yet strong material such as acetate sheet. The drum is formed by a rolled side sheet 7 (Figure 2) having an inturned bead 8 at its bottom margin and a somewhat similar inturned bead 9 at its top margin. A bottom plate 11 rests upon the lower bead 8 and serves as a bottom closure for the container drum. Preferably, the acetate sheet forming the side wall 7 is of an opaque nature so that the contents of the hand bag are not

readily visible and preferably likewise bears a pigmentation or coloring of a suitable nature, for example, dark red.

Adapted to cooperate with the circular-cylindrical drum, I provide a cover generally designed 5 13. The cover includes a top plate 14 preferably of acetate material and is either opaque or transparent. The cover likewise includes a depending circular-cylindrical flange 16 having a lower inturned bead 17 and an upper inturned bead 18. Preferably the upper bead is secured to the cover sheet 14 by an adhesive junction 19. The flange 16 is made of acetate sheet of a clear or transparent nature. The dimension of the lower bead 10 17 is such that the cover frictionally engages the container 6 without difficulty.

In order to relate the cover and the drum in a more or less permanent fashion, yet to allow ready access to the interior of the container, I 15 provide a cord 21 which passes through an aperture 22 in the cover plate 14 and likewise passes through a similar aperture 23 in the side wall 7. In the present instance, the cord 21 is doubled back upon itself and consequently passes in 20 double form through apertures 22 and 23. The ends of the cord are provided with knots 24 to preclude ready removal at that end. A similar cord 26 is interengaged with the cord 21 and similarly passes through the cover and the side 25 wall of the container. In this way, the cover can be slid along the cords 21 and 26 for ready access to the interior of the container yet is always easily returned to its appropriate position on the container. The cords 21 and 26 likewise 30 serve as a hand hold for the hand bag.

The bag as so far described can be displayed for sale in a store. It is light, simple, inexpensive and attractive, yet cannot be readily identified or distinguished from other bags of similar manufacture. In order to have an element of personal 35 distinction and to render an individual bag readily identifiable, I provide means for displaying the name or monogram or other indicia of the owner. While that can be accomplished 40 at the point of sale, still in many department stores, for example, it is not desirable to have special equipment and personnel nor to take time for monogramming or otherwise marking the hand bag.

Under the circumstances, I preferably enclose 45 a card (not shown) within the container at the factory and arrange that the card be mailed to the factory by the purchaser of the hand bag for manufacture of appropriate identification. Upon receipt of such card from the purchaser,

the manufacturer provides a sheet 31 (Figure 3) of a transparent acetate material flexible enough to bend to the curvature of the flange 16. The height of the sheet 31 is appropriate to let it pass between the inturned portions of the flanges 17 and 18 and is sufficient to permit the sheet to inter-engage between the flange 16 and the beads 17 and 18. When appropriately introduced therebetween, the sheet 31 remains in position against accidental dislodgment. The 10 flexibility of the sheet helps such ready introduction.

The sheet 31, being transparent, is appropriately provided, for example, by hot stamping with suitable indicia 32. These are preferably in marked contrast with the opaque nature of the body of the drum. For example, a gold or silver leaf hot stamping provides indicia 32 which are readily visible through the transparent outer flange 16 and are also in contrast with the back red background of the drum. Since the sheet 31 itself is transparent, it is not especially distinguished from but appears to be part of the transparent flange 16. The general appearance is of a monogram or name or other indicia affixed to the flange of the cover itself and in marked contrast or distinction with the general body of the drum. This is particularly true when the indicia 32 are in outlined letters. If they are in silver or in gold outline on a transparent sheet 31, for example, they are not very readily apparent or distinct when viewed alone under nor-

mal circumstances. But when they are held in place by the beads 17 and 18 and are positioned over the contrasting background provided by the drum, they are immediately distinctive and apparent so that the hand bag as a whole is readily distinguished and is appropriately ornamented.

5 What is claimed is:

A hand bag comprising a circular-cylindrical drum having a pair of diametrically disposed apertures in the wall thereof, a cover having a top plate with a pair of diametrically disposed apertures therein and having circular-cylindrical flange adapted to overlie said drum, and a cord forming a handle for said hand bag and passing 10 through the apertures in said cover from the outside to the inside of said cover and engaging said drum by passing through the apertures therein 15 from the inside to the outside of said drum.

PERCY BARKER.
